METHOD OF ELECTROCHEMICAL TREATMENT OF UNSATURATED HYDROCARBON
COMPOUNDS RESULTING FROM THE CRACKING OF OILS
Original Filed April 24, 1919

INVENTOR
Donald L. Thomas,
BY His Attorney,

UNITED STATES PATENT OFFICE.

DONALD L. THOMAS, OF NEW YORK, N. Y.

METHOD OF ELECTROCHEMICAL TREATMENT OF UNSATURATED HYDROCARBON COMPOUNDS RESULTING FROM THE CRACKING OF OILS.

Original application filed April 24, 1919, Serial No. 292,425. Divided and this application filed February 9, 1925. Serial No. 7,886.

This invention relates to the electrochemical treatment of unsaturated hydrocarbon compounds resulting from the heat cracking of oils and has for its objects the stabilization of such compounds through the hydrogenation, polymerization or recombination thereof whereby the yield of condensable liquids is increased and valuable light hydrocarbon liquids of superior quality to that ordinarily produced by the usual high pressure cracking process can be obtained by the simple distillation of the resultant products without necessitating expensive acid refining treatment.

In my co-pending application No. 292,425 for process and apparatus for converting high-boiling oils or hydrocarbons into stable low boiling oils or hydrocarbons filed April 24, 1919, of which this application is a true division, there is described a novel method and apparatus for the pyrogenetically cracking of hydrocarbons by heat and pressure for the purpose of producing unsaturated hydrocarbon compounds which are suitable for being subjected to the electrochemical treatment hereinafter described.

As stated in said pending application, the amount of heat required is that which is necessary to furnish the expansive force needed to bring about rupture of the original hydrocarbon molecule, whilst pressure is necessary to force together the resulting nascent reactive products into more concentrated and intimate relationship so that reactions involving new molecular arrangements can thereafter take place in a second and preferably separate stage of the process. The reactions of this last stage of the process are greatly facilitated by the action of the electric current, which plays the part of a catalytic element, affecting the time-factor of the reaction and making possible the accomplishing of results that are unattainable by other and less energetic means.

As all cracking operations require more or less mechanical force for their development, it is customary to obtain this force from the expansive power of the oil-vapors developed under pressure. The pressure in this last mentioned case, when present during the decomposing stage of the process, naturally opposes the expansive force needed to bring about rupture of the hydrocarbon molecules, hence, at this point it is

a detriment, whilst during recombination, as it favors reunion of the cracked products, it is a sine-qua-non of operation.

From these facts I have ascertained that the cracking operation should take place in the following series of steps:

1st. A vaporization of the oil, under pressure, at moderate temperatures, for example at from 400° to 500° C., to develop sufficient working force to operate the apparatus.

2nd. Cracking of the oil-vapor at higher temperatures, for example at from 500° to 800° C., under low pressure to produce chemical dissociation.

3rd. A condensation of the cracked products, under high pressure in order to favor molecular recombination.

4th. Treating the cracked products while under pressure, to the silent electric discharge or electric corona, either before or after condensation to the liquid state, to produce hydrogenation and polymerization.

At present there are at least three recognized standard methods of cracking oils by means of heat and pressure, each capable of illustration by a type. First, the so-called Burton-process, consisting of heating a large body of liquid oil in a large tank or still, and condensing the vapors generated therein under pressure. Second, the so-called Rittman-process, consisting of heating oil-vapors under pressure, in a large (12 inch) tube and then condensing the cracked products so produced under pressure.

Third, the so-called Hall-process, which consists of heating the oil in a long coil of small bore pipe, (1 inch diameter and 600 feet long) releasing the pressure so produced, by expanding the vapor down to atmospheric pressure in a large tank or chamber and then again recompressing the gases and vapors by means of a mechanical compressor, in order to polymerize them, and then finally condensing the resulting products to liquid under pressure.

To these may be added a fourth type, as exemplified in my said co-pending application, wherein an oil, as fuel oil of, 850 S. G. is vaporized under pressure and the vapor so generated, passed into a region of low pressure. High temperature is then applied to the vapors in this region of low pressure

in order to crack the same, and the cracked products are then passed to a region of high pressure for recombination and polymerization.

Finally they are subjected to the action of the silent electric discharge, in this region of high pressure, either whilst in the vapor state or after condensation to the liquid state, and finally condensing and removing the finished product. All this to be accomplished without the use of mechanical pumps or compressors.

The specific example of a one tube installation is fully set forth and described in the following specification and drawings forming a part thereof in which

Figure 1 is an elevation, partially in section of a form of the apparatus wherein the cracked products are first treated in a digester, and are then submitted to the action of a corona or silent electric discharge, either direct or alternating, the treated products being in a liquid state.

Fig. 2 is also an elevation partially in section of a form wherein the digester is dispensed with its place being taken by an electrical treating chamber adapted to function as a digester and polymerizer, by acting on all of the cracked products whilst existent in the form of vapors and gases before being condensed to the liquid state. Figs. 3 and 4 show longitudinal and cross sections of the pieces of iron pipe used in the digester.

One of the features of this invention is a means by which the unsaturated hydrocarbons inevitably found in all products that are cracked by heat may be permanently stabilized. These compounds have a very deleterious effect on motor-fuel produced by cracking as such fuels in the course of time deposits a gummy resinous residue very injurious to the action of the valves of internal combustion engines. The removal of such products by means of sulphuric acid is a very serious problem of the refinery, and one that so far has defied a satisfactory solution on account of the large loss of valuable material involved. These products if they could be stabilized would form a very valuable addition to the fuel itself, adding greatly to its thermal or heating capacity.

It is purposed to show herein how this result can be accomplished. As a preliminary to a presentation of the means to be used for

this purpose, it may be stated that the effects are predicated on the experimental results attained by such men as J. N. Collie, H. Jackson and D. Northall Lowrie, and F. Skaupy working with the electric current in the form of a corona or silent electric discharge through hydrocarbons, wherein it is shown that the action of electric discharges, both alternating and direct, on various saturated and unsaturated hydrocarbon compounds leads to the conclusion, that as a

general rule, saturated compounds are broken down to simpler molecules, whilst unsaturated compounds (such as ethylene and olefines) are converted into complex polymerized substances, thus, in the case of paraffin derivatives the general tendency is for unsaturated bodies to give polymerized varieties under the influence of the silent discharge, whilst saturated compounds, under similar conditions, yield substances of simpler structure. At the same time it must be pointed out that the silent electric discharge under proper conditions (such as when hydrogen or gases containing hydrogen are present) has the power to bring about hydrogenation of unsaturated compounds, this has been pointed out by A. de Hemptinne in his U. S. Patent No. 797112. Considerable use is made of this last feature because in the method outlined herein, it is proposed to pass the gases generated in cracking the hydrocarbons, into the electric field along with the condensable hydrocarbons or the liquids derived therefrom, the whole being treated in such manner that the gases, and the condensable vapor or the liquid are brought into intimate contact with each other whilst being submitted to the action of the electric effluvia. The result of the action will be to bring about a union of more or less of these gases with the vapor or liquid, along with polymerization of unsaturated compounds, whether existant in gas, vapor or liquid, thus materially increasing the yield of condensable liquids. Moreover it will be found that the resultant liquids are perfectly stable, the double-bonds of the unsaturated molecules having been satisfied or eliminated by combination, thus, stabilizing the product. When purified by a further simple distillation the liquids are ready for use.

One method of carrying out the process is illustrated in Figure 1. Here an electrical corona or silent electrical discharge is created directly in the body of the liquid hydrocarbon. To many, the idea of producing a corona discharge directly in a body of liquid oil, will seem revolutionary, the phenomena however, is well known to electrical engineers; see articles by F. W. Peck, Jr., in "The General Electric Review", vol. 18—1915 page 821, and by W. S. Moody and G. Faccioli in "Trans. Amer. Inst. Electrical Engineers" vol. 28—1909 page 769.

In its way electrical corona in oil is quite as distinct a phenomena as in gases or air, and is due to an ionization of the hydrocarbon molecules, about the only difference between the two is that in oil the corona is not quite as steady or definite as in air. In oil, it appears to start quite suddenly, and to extend much further out from the electrode, than corona in air, whilst it is much more difficult to detect the starting point.

The dielectric strength of oil, that is to

say, the disruptive gradient or voltage required to bring the ions up to an ionizing collision velocity, seems to be fairly low, and according to F. W. Peck, Jr., is about 36 kilovolts, therefore it may be said oil has a low dielectric strength in bulk.

Referring to Figure 1, the pipe *a* is adapted to receive cracked products while still under the final pressure and at the temperatures to which they were subjected in the final space or chamber of the cracking unit of the refinery and without previous cooling of the said products, such for example as the lower diverging Venturi mouth piece of the apparatus (not shown) described in my co-pending application aforesaid.

It is to be understood that the object of the digester *b* is to treat the hydrocarbon material by exposing it to large surfaces *b''* by which it is naturally adsorbed, whilst the speed of travel of the vapors is reduced to a minimum. Such surfaces exert a catalytic or some similar effect on the cracked material which is in a highly reactive condition, bringing about hydrogenation, polymerization and recombination of the nascent fragments of the original hydrocarbon molecules into new molecular arrangements. This action is of course assisted by pressure, because, according to the law of mass action, reaction velocity is proportional to concentration and concentration is directly proportional to pressure. Surface action has a great deal to do with the effects produced as is pointed out by Professor Wilder D. Bancroft in a "Note on contact catalysis" Journal of Physical Chemistry, June 1918, page 433, wherein it is shown that the equilibrium and velocity relations of physical substances is markedly altered by adsorption, much freer play being given to physical and chemical forces thereby. Whatever the cause may be, the action is unquestionable, being more cumulative than instantaneous and it takes place whether the hydrocarbon is in liquid or gaseous state when brought into contact with the baffling material.

It appears that two entirely different reactions are involved in the formation of light hydrocarbons. The first one involves slitting of saturated bodies into saturated and unsaturated, paraffins and olefines of lower molecular weight resulting, with the splitting out of hydrogen, and consequent increase in volume of cracked products. Diminished pressure facilitates and accelerates this stage. The next step, however, requires the condensation and hydrogenation of the unsaturated bodies, and pressure naturally favors this. It is true that hydrogen may split out also at this point, but even so, condensation and hydrogenation is difficult to effect under diminished pressure, therefore sufficient pressure must be provided to effect this condensation since the natural

tendency of pressure is to force homogeneous gas reactions in the direction in which a reduction in the number of molecules takes place, accompanied by synthesis in the reactive material.

Referring to Figure 1, the external walls of the digester therein shown is closed in heat retaining or insulating jackets of asbestos or other suitable material as indicated by the reference letter *b'*.

It will be seen from the above that there is no inherent difficulty in treating the cracked liquids to the electric effluvia and Figure 1 shows how this may be carried out.

Here, in this method the condensed liquids along with the non-condensable gases, are led into a receiving tank space, 64, formed usually in the upper part of the treating receptacle, 65, by means of a pipe 66, and valve, 67, that connects with the condenser 68.

The receptacle 65, preferably consists of strong steel tube having an inner enameled surface 65' of glass, porcelain or other dielectric material, the dielectric surface serving to prevent danger of a short circuit by a dynamic arc following a spark-over, as when the oils are very bad and contain electrically conductive material, at the same time the dielectric is useful insuring a uniformly distributed electrostatic field. The upper portion of the receptacle, 65, is closed by an insulating stopper 70, thus separating and hermetically sealing off the tank-space 64 from the main body of the receptacle 65.

The main body of the receptacle is provided with an outlet tube 71 near its upper end, for the escape of the treated gases and liquids to the storage tank 90 and recirculating gas-line 91. An electrically insulated

metallic tube or pipe 72 extending from the interior of the tank-space 64 into the bottom of the main receptacle 65, serves to deliver the liquids and gases discharged into the space 64 from the condenser to the bottom of the main receptacle whence they pass upwardly outside of the tube 72 to the pipe 71.

This insulated metallic tube 72 constitutes the inner co-operating electrode to the outer walls of the treating chamber 65 which form the outer electrode. As indicated, this inner electrode is preferably provided with sharp projections, formed by thin metallic discs *d* spaced short distances apart by washers *e* of smaller diameter, the whole being held together on the pipe 72 by suitable screw-connections and nuts. The construction is such that this inner electrode is separated a greater distance from the outer electrode, at its ends, than at the region

where the projections are provided and where the electric action takes place. The oils and the gases in thorough admixture therewith, on being discharged into the lower part of the treating chamber, rise to the discharge tube 71 and in so doing pass

through a series of intense electrostatic fields, created between the discs of the inner electrode and the walls of the treating vessel, by some suitable source of high potential electricity for example, a high potential transformer 73, having one of its leads 74 attached to the inner electrode and its other lead 75 grounded at 75'. Co-operating with this the metallic body of the receptacle 65, 10 is by means of the wire 76 grounded at 77. This arrangement is for the purpose of preventing danger to operators from electric shock. The positioning of the electrodes, one within the other, is an advantageous 15 one, as it gives a very dense electrostatic field of high gradient near the inner electrode, but of relatively low gradient at the outer electrode or wall of the treating chamber which facilitates the production of 20 the corona discharge.

The liquids after passage through the treating chamber are submitted to further simple distillation treatment, to remove polymerized resinous products and are then 25 ready for use. The advantages of this method of treatment over that requiring the use of sulphuric acid, with its large attendant loss of valuable material at once recommends the method to the attention of those 30 interested in securing a rapid and economical method of treating cracked hydrocarbons to render them suitable for the market.

Although I have disclosed a suitable form 35 of apparatus for practicing the invention, I do not limit myself to these special devices or constructions herein specified, as I believe it is broadly new with me, to utilize the effects of passing a high potential electric current through a body of liquid hydrocarbons in order to effect the hydrogenation, 40 polymerization and synthesizing of the unsaturated compounds existing in such cracked oils as specified above as products suitable for treatment.

45 In the form of the invention disclosed in Fig. 2 the important function of the digester of Figure 1 is dispensed with, its place being supplied by an electric polymerizer, adapted to function both as digester and polymerizer by acting on all of the cracked hydrocarbons while they are in the vapor state. This arrangement has certain advantages due to the fact that not alone is the 50 plant rendered more compact, but the corona discharge itself is somewhat easier to produce and maintain in vapors and in gases than it is in liquids.

55 In order to make the construction plain, it may be said that the cracked products are conducted by the pipe *a* to an electrical treating chamber *c* as shown, consisting of a steel tube about 12 inches internal diameter and 15 ft. high. To its base is fitted a conical extension or sludge-box 78, having an 60 automatic-float-controlled-valve 78', for re-

moving liquid residues, as previously explained, and which maintains the liquid level at the point 78''—78''.

Suspended in the tube *c* and electrically insulated therefrom, is a high tension discharge electrode 79, formed of a $\frac{1}{2}$ inch steel rod, having thereon in equally spaced relationship, thin metal discs about 3 inches in diameter and spaced apart by metal washers 1 inch in diameter and $\frac{1}{2}$ inch thick. 75 To the top of the electrode 79 one wire 80, of a high tension alternating current electrical transformer 81, is attached, the other wire 82 of the transformer being grounded at 83. To the base of the electrical treating 80 chamber and in electrical contact therewith at the point 84, there is attached a wire 85, which in its turn is grounded at 86. The object being to avoid danger of electrical shock when the high-tension transformer is being 85 operated.

90 By causing a corona discharge to take place between the walls of the tube and the central electrode, oil-vapors on being passed through this tube are subjected to a series of intense electrical fields of high gradient near the central electrode, provided by the edges of the discs, and the unsaturated products contained therein are rapidly polymerized and built up according to principles already 95 enunciated. The tube *c*, should have a heat insulating jacket *b'*, around it to prevent loss of heat and consequent undesired condensation at this point.

99 From the electrical treating chamber *c*, the vapors pass to the water-cooled condenser 68', by means of a pipe 87, and here the condensable portion of the cracked products is reduced to liquid form and flows into the storage tank 90' the non-condensable gases 105 escaping by way of the connection 88, to the pipe line 91' to be returned to the system for recirculation therethrough for carrying out the various functions already specified.

110 The part played by electricity in this process should be clearly understood, as it is important to grasp the idea that the current is not used for the purpose of decomposing the hydrocarbons, such decomposition as occurs being merely incidental, the main purpose and object in view being the hydrogenation 115 and polymerization of the cracked products, so as to completely stabilize the resulting product of the reaction. This the current does in a very thorough and rapid manner 120 as has been pointed out above.

125 I am perfectly familiar with the fact that it has been proposed to use the electric current as a means of decomposing hydrocarbons in order to produce lower-boiling products, the use of direct-current for this purpose having been patented by J. H. Robertson (U. S. Pat. No. 1238339) and the use of alternating-current having been 130 patented by L. B. Cherry (U. S. Pat. No.

- 1229886). But so far as my knowledge goes, it has never been proposed to use the electric current as a means to bring about hydrogenation and polymerization of the cracked products, after the cracking operation itself has been completed by heat and pressure in the usual manner. This forms a clear and distinct line of demarkation between this method and the processes referred to above.
- 10 In the one case it acts as the cracking medium, in the other case it acts as the synthesizing medium. This use of the current completely eliminates the gummy material deposited by most cracked gasolenes and which
- 15 is due to a slow polymerization of the unsaturated compounds which they contain. These compounds are completely polymerized once and for all by the current and are then, after condensation, removed by a simple distillation of the final product. A material saving in the way of refinery treatment is thus effected and a much higher grade product produced.

Under the influence of the pressure and the action of the electric current, recombination, polymerization and hydrogenation rapidly occurs in the cracked products, which are then passed to the condenser for reduction to liquid form whilst still under pressure.

The exit or operative pressure on the products from the previous cracking operation described in my said co-pending application which are introduced through the pipe *a* will be about 135 lbs. per square inch and the temperature will vary between 500° C. and 800° C. for example, between 500° C. to 600° C. where gasolene is desired or from 600° C. to 700° C. where aromatic hydrocarbons are desired.

The digester has already been described, the only remarks to be added are that it is provided with a removable cap, 62, so that the filling material can be removed at any time. Further an automatic sludge-valve 63, is provided which keeps the liquid level at 63'-63', as shown.

The digester *b* consists of a stout steel chamber 24 inches internal diameter and 12 feet high, filled with short pieces of 1 inch iron pipe, such as illustrated in Figures 3 and 4.

Having thus described my invention, what I claim and desire to obtain by Letters Patent of the United States is:

1. The process which consists in subjecting the pre-cracked material, resulting from subjecting high boiling point hydrocarbons to a heat and pressure cracking process in which the principal portion of the heat employed is generated without subjecting the material to the influence of a silent electric discharge, to the influence of a silent electric discharge of sufficient intensity to materially polymerize such materials, whereby the same

are substantially stabilized and otherwise improved.

2. In the process of cracking hydrocarbons and then of hydrogenating pre-cracked unsaturated hydrocarbon compounds whilst in the dissociated state, the step which consists in subjecting a physical mixture of such compounds and of a gas rich in hydrogen to the discharge of a high tension electric current, thus causing rearrangement of the molecular structure of the hydrocarbons whereby hydrogen is taken from the gas and caused to unite with the unsaturated hydrocarbons to produce stable saturated hydrocarbons.

3. In the process of cracking hydrocarbons and then of hydrogenating pre-cracked unsaturated hydrocarbon compounds whilst in the dissociated state, the step which consists in subjecting a physical mixture of such compounds and of a gas rich in hydrogen to the discharge of an electric corona, thus causing rearrangement of the molecular structure of the hydrocarbons whereby hydrogen is taken from the gas and caused to unite with the unsaturated hydrocarbons to produce stable saturated hydrocarbons.

4. The electrochemical process of treating pre-cracked unsaturated hydrocarbon compounds resulting from heat cracking of oils, in order to polymerize the same, that step which consists in subjecting such compounds to the silent discharge of a high tension electric current, while under the simultaneous influence of high temperature and pressure in order to produce by combination of their molecules a final stable product of different gravity and boiling point from the compound originally treated, substantially as described.

5. The process of hydrogenating pre-cracked unsaturated hydrocarbon compounds which consists in subjecting a physical mixture of such compounds while in a dissociated state and of a gas relatively rich in hydrogen to the discharge of a high-tension electric current, thus causing rearrangement of the molecular structure of the hydrocarbons whereby hydrogen is taken from the gas and caused to unite with the unsaturated hydrocarbons to produce stable saturated hydrocarbons.

6. The process of treating pre-cracked hydrocarbon compounds, resulting from the cracking at a cracking temperature of high-boiling point hydrocarbons, which consists in subjecting such products while in a nascent state and comprising a mixture of condensable and non-condensable vapors and gases, the latter rich in hydrogen, to the action of an electric corona in order to hydrogenate and polymerize the condensable portions thereof.

7. The process which consists in subjecting the pre-cracked products from the cracking

of high-boiling point hydrocarbons at a cracking temperature and while in the presence of the uncondensable gases, rich in hydrogen, resulting from such previous treatment, to the action of an electric corona for a sufficient period of time to effect substantial hydrogenation and polymerization of such cracked products.

8. The process of improving pre-cracked

hydrocarbons, which consists in exposing the same while at a high temperature and in vapor phase to the action of an electric corona in order to polymerize and hydrogenate the same.

Signed at New York, in the county and State of New York this 7th of February 1925.

DONALD L. THOMAS.
